UNITED STATES PATENT OFFICE.

GOTTFRIED P. BAUMANN, OF CHICAGO, ILLINOIS, ASSIGNOR TO IDEAL STITCHER & MANUFACTURING COMPANY, OF CHICAGO, ILLINOIS.

STITCHING MACHINE.

Application filed June 27, 1921. Serial No. 480,742.

To all whom it may concern:

Be it known that I, GOTTFRIED P. BAUMANN, a citizen of the United States, residing at Chicago, in the county of Cook and State of Illinois, have invented a certain new and useful Improvement in Stitching Machines, of which the following is a full, clear, concise, and exact description, reference being had to the accompanying drawings, forming a part of this specification.

My invention relates to stitching machines and has to do more particularly with the construction of an improved clincher block and supporting post arrangement of the type used for stitching the ordinary cardboard or other paper boxes.

In connection with stitchers of this type long clincher-block supporting posts have been provided held in a normal upright position and adapted to be unlocked and tilted forwardly by a foot treadle. Heretofore, however, great difficulty has been met with in the use of such posts in that they were very easily thrown out of alignment so that

the clincher block would not be maintained properly beneath the former and driver and the head of the stitching machine.

One of the features of my invention obviates this latter objection by the provision of a three-way adjustment for the clincher block whereby it may be adjusted vertically to the proper height, and in two crossing horizontal directions, such as transversely and from the back toward the front, to definite vertical alignment with the former and driver.

Another feature of my invention is the provision of an improved and simplified vertical adjusting means. A further feature is the provision of an improved and simplified post locking and actuating means.

Other features of my invention will be more particularly pointed out in the ensuing part of the specification and appended claims.

Referring now to the accompanying drawings for a better understanding of my invention

Fig. 1 is a side elevation showing an ordinary wire stitcher with my improved clincher block and post construction applied thereto;

Fig. 2 is a face view of the post arrangement shown partly in section along the line 2-2 of Fig. 5;

Fig. 3 is a transverse sectional view along the line 3-3 of Fig. 2 showing the yielding stop for the vertical adjusting mechanism;

Fig. 4 is a top or plan view of the post showing more particularly the transverse clincher block adjustment, this view being along the line 4-4 of Fig. 2;

Fig. 5 is a vertical section through the post supporting bracket and post along the line 5-5 of Fig. 6; and

Fig. 6 is a top or plan view of Fig. 5.

Referring now more in detail to the preferred construction as illustrated, I have shown an ordinary type of stitcher having the usual head 10 and base 11, the head containing the usual wire feeding forming and driving mechanism. A tiltable post arrangement is supported upon the base 11 of the stitcher and comprises an anvil post base bracket consisting of a base portion 12 and uprights 13-14 which pivotally support the post base 15. To this end a shaft 16 passes through the sides 13-14 and the hub 17 of the post base.

The base plate 12 has a number of suitable holes 18 through which bolts are passed for securing it to the base of the machine. An upright extension 19 is provided at the rear of the base bracket and carries an adjustable stop screw 20 adapted to engage a stop surface 21 on the post base 15. This screw 20 is held by a lock nut 22 which also clamps a plate 23 for holding a retrieving spring 24 which is attached to the post as shown in Fig. 1. By means of the stop screw 20 the post may be adjusted so as to assume the proper vertical position in alignment with the former and driver carried by the stitcher head.

A treadle actuated operating and locking means for the post is provided and to this end a treadle support 25 is pivotally attached to lugs 26-27 by a pin 28 which also passes through the outer uprights 13-14. An angle iron 29 is suitably secured to the treadle support 25 and carries a treadle step 30 at the forward end thereof.

The treadle post actuating and locking means is preferably controlled by the single treadle member which is arranged to unlock the post by its initial or preliminary movement after which the succeeding movement thereof will move the post forwardly clear of the stitcher head so that the box may be placed thereover as indicated by the

dotted lines in Fig. 1. To this end I provide a link connection between the treadle and the post support in the nature of a lost motion device comprising a link 31 having a forked lower end 32-33 which embraces the treadle support 25 and pivotally attached thereto by means of a pin 34. The upper end of the link 31 extends between lugs 35-36 on the post support and connected thereto by means of a pin 37 extending through a slot 38 in the link. I thus provide a lost motion connection requiring a preliminary movement, the extent of which is determined by the length of the slot 38, before the movement of the post commences. The post, of course, is normally held in an upright position by the spring 24 but in order to hold the treadle in its upper normal position I provide a treadle spring 40 connected at its lower end to the pin 34 and its upper end to a lug 41 by means of a cap screw 42.

In order to prevent a too far forward movement of the post I secure a stop plate 43 across the front of the post supporting uprights 13-14.

Now as to the post locking means I preferably provide cooperating locking plates on the post support hub and the treadle consisting of a hardened steel plate 45 secured in a recess 46 of the hub. The cooperating treadle plate is also preferably a hardened steel member 47 suitably fastened to the treadle and sized to lock against the post plate 45 and hold the post in an upright position to prevent a forward movement thereof unless the treadle is stepped on.

Supported in the post bracket 15 is a clincher block post 48 suitably and rigidly held in place preferably by threading into the bracket at 49. This post 48 is preferably a steel tube into the upper end of which is driven a flanged sleeve 50 rotatably supporting an adjusting nut 51 knurled at its periphery 52 so that it may be grasped by the hand of the operator for rotatable adjustment. This adjusting nut 51 carries a clincher block support 53 having a depending shaft threaded at 54 into the adjusting nut 51 and the lower end 55 extending downwardly into the collar 50. The end 55 is slotted at 56 through which a pin 57 extends so as to prevent relative rotation of the clincher block supporting member 53 and the post 48 to thereby maintain the clincher block support always at a definite relation to the stitcher head, although adjusted vertically by means of the adjusting nut 51.

At the upper end of the clincher block support 53 is a clincher block 58 comprising a block set in a transverse slot 59 in the upper end of the support 53. Thus the clincher block may be shifted transversely into proper alignment with the former and driver. A set screw 60 is threaded through the wall

of the support 53 so as to hold the clincher block in its adjusted position. This transverse adjustment provided in connection with the vertical adjustment of the clincher block overcomes the great difficulty heretofore experienced in maintaining the clincher block and former in proper alignment. The clincher block post being extremely long ordinarily three to four feet long, the slightest displacement of the base, due to the hard wear to which such a machine is subjected, climatic changes and warping, will throw the clincher block off enough to prevent a most effective stapling operation. All this, however, is obviated by the construction which I have provided.

In connection with the vertical adjustment referred to I provide a yielding lock in the nature of a spring pressed stud 61 adapted to engage the adjacently positioned recesses 62 in the adjusting nut 51 so that it will be suitably retained in its adjusted position although yieldingly held so that it may be manually rotated to vertically adjust the clincher block when necessary.

In the operation of the device, the operator places his foot upon the step 30 of the treadle, pressing it downwardly so that its preliminary movement unlocks the locking plates 45-47. This preliminary or unlocking movement of the lever is permitted due to the lost motion at the slot 38 of link 31 after which the continued downward movement of the treadle causes the link 31 to operatively engage pin 37 and tilt the post forwardly so that the clincher block will clear the stitcher head as indicated by the dotted lines in Fig. 1. The box is then placed over the post as indicated by the dotted lines 65. The foot is now removed from the treadle and spring 24 thereupon returns the post to its normal upright position and treadle spring 40 returns the treadle to its normal and locking position. The operator now steps upon the usual stitcher actuating treadle and the box may be moved along on the clincher block and stitched as desired. To remove the box, the treadle is again stepped upon thereby unlocking the post and tilting it forwardly to a position clear of the stitcher head.

What I claim as new and desire to secure by U. S. Letters Patent is:

1. In a stitching machine, a tubular clincher-block post, a rotatable sleeve extending upwardly out of the post, a clincher-block support having a depending stud threaded down into the sleeve whereby rotation of the sleeve will adjust the clincher-block support, and a stationary sleeve positioned between the post and rotatable sleeve carrying means for yieldingly holding the rotatable sleeve in adjusted position.

2. In a stitching machine, a tubular clincher-block post, a rotatable sleeve extending

- upwardly out of the post, a clincher-block support having a depending stud threaded down into the sleeve whereby rotation of the sleeve will adjust the clincher-block support, 5 means to prevent relative rotation of the support and post, and a stationary sleeve positioned between the post and rotatable sleeve carrying means for yieldingly holding the rotatable sleeve in adjusted position.
- 10 3. In a stitching machine, a tubular clincher-block post, a rotatable sleeve extending upwardly out of the post, a clincher block support having a depending stud threaded down into the sleeve whereby rotation of the sleeve will adjust the clincher-block support, and a clincher-block transversely adjustably carried at the upper end of said support substantially within the outer confines thereof.
- 15 4. In a stitching machine, a tubular clincher-block post, a rotatable sleeve extending upwardly out of the post, a clincher-block support having a depending stud threaded down into the sleeve whereby rotation of the sleeve will adjust the clincher-block support, means to prevent relative rotation of the support and post, and a clincher-block transversely adjustably carried at the upper end of said support substantially within the outer confines thereof.
- 20 5. In combination with a stitching machine head and base, a clincher-block post base bracket, a clincher-block post pivotally mounted on said bracket and having a normal upright position, a clincher-block, and adjusting means whereby said clincher-block may be adjusted in two horizontal directions to a normal definite vertical alignment with the head.
- 25 6. In combination with a stitching machine head and base, a clincher-block post base bracket, a clincher-block post pivotally mounted on said bracket and having a normal upright position, a clincher-block, and means for adjusting said clincher-block in three directions relative to the head.
- 30 7. In combination with a stitching ma-
- chine head and base, a clincher-block post base bracket, a clincher-block post pivotally mounted on said bracket and having a normal upright position, a clincher-block, and means for adjusting said clincher-block in two horizontal directions and vertically to a definite relation with the head. 50
8. In a stitching machine, a clincher-block post base bracket for mounting on the base of the stitcher, a clincher-block post pivotally mounted on said bracket so as to tilt forward from a normal upright position, a treadle pivotally secured to said bracket, interengaging locking plates on said treadle and post to normally lock the post in its upright position, and a link connecting said treadle and post but having lost motion so as to permit a preliminary movement of the 55 treadle to unlock said plates and a further movement to tilt the post.
9. In a stitching machine, a clincher-block post base bracket for mounting on the base of the stitcher, a clincher-block post having a hub pivotally secured to said bracket so as to permit tilting the post forward from a normal upright position, a treadle pivotally secured to the bracket beneath the hub, a locking plate set in a recess in the hub periphery, a cooperating locking plate carried by the treadle to normally lock the post in its upright position, and a lost motion connection between the treadle and post so as to permit a preliminary movement of the 60 treadle to unlock the plates and a further movement to tilt the post. 65
10. In a stitching machine, a tubular clincher-block post, a clincher-block supporting post adjustably extending up out of the tubular post and of substantially the same cross-sectional area, a transverse slot across the top of the supporting post, and a clincher block adjustably held for movement along in said slot. 70
- 75 In witness whereof, I hereunto subscribe my name this 16th day of June, A. D., 1921.

GOTTFRIED P. BAUMANN.
